RADIO RECEIVER

Frank Maurice Hills, Roehampton, London,
EnglandApplication October 16, 1945, Serial No. 622,582
In Great Britain November 8, 1943

1 Claim. (Cl. 250—14)

1

This invention relates to radio receivers for domestic and like uses.

The object of the present invention is to provide a receiver which is so small and light that it can be put into and taken out of the usual domestic light socket or fitting as easily as a lamp bulb, while at the same time ready access may at any time be obtained to any of the components without permanently destroying any part of the receiver.

The invention will best be understood by referring to the following detailed specification of certain preferred embodiments thereof, taken in connection with the appended drawings, in which

Fig. 1 is a schematic diagram of a receiver circuit suitable for use as a part of the invention.

Fig. 2 is a perspective view of a combined lamp and receiver, parts being broken away.

Fig. 3 is a similar view of a modified arrangement, and

Fig. 4 is a vertical sectional view of the receiver portion alone, showing the electrical connectors used therewith.

A receiver according to the present invention comprises a frame or casing in which are removably assembled the valve or valves and other circuit elements of a radio receiver connected to a plug, socket or the like, closely associated with the frame or casing for connecting the circuit to a socket, plug or like power supply termination, the circuit components being of such weight and dimensions that the whole assembly can be supported by the socket, plug or like element from which the electric power is to be taken. Preferably the said frame or casing also carries the loud-speaker actuated by the receiver circuit, and whenever herein I refer to the "frame" or "casing" it is to be understood that such expression does not mean an evacuated envelope.

The connector associated with the receiver casing should be of suitable form and size to engage with a co-acting connector of any type normally used domestically. Thus, if a plug, it may conveniently be of the 5 amp. bayonet or screwed plug and socket, or 2- or 3-pin type suitable for coupling with sockets commonly used in domestic lighting or wall points. This connector may be rigidly attached to the receiver frame or casing (thus rendering it suitable for plugging directly into an electric wall-socket as well as a light pendant), or may be attached thereto by a very short length of strong but flexible electric cable, e. g. heavy duty, rubber sheathed cable. The latter arrangement, while unsuitable for supporting the receiver from a wall socket, might be pre-

ferred for a receiver intended to be plugged into a light pendant. It is to be understood, however, that when such a short length of cable is employed, it will be much shorter than that supplied with the so-called "midget" receivers now on the market and which is of considerable length to constitute a load resistance. Such midget receivers, in any case, are much too heavy to be safely suspended from an ordinary light socket, and are not constructed with a view to being so suspended.

Since it is to be supportable from a domestic type of electric point, it is important that the weight and dimensions of the receiver be kept as small as possible, subject to the required performance of the circuit, and accordingly a receiver embodying the present invention weighs not more than 2 pounds, and is preferably not larger than 6 inches in any overall dimension. This size may, however, be modified if the receiver casing is designed also to perform any other function. Thus it may form, or be built into, an electric lampshade or reflector in which case it may, for example, be in the shape of a domed, conical or pyramidal box noticeably greater than 6 inches in two dimensions but correspondingly less in its third dimension. In such an arrangement space may be provided within the box to receive other elements not necessarily forming part of the receiver circuit, e. g. electric lamps.

A receiver circuit having reasonable performance within the limit of weight indicated above is designed, according to the invention, by careful selection of light-weight components. Thus the valves used are preferably of the kind known in the radio industry as midget, bantam or miniature valves; and in the circuit (which may comprise one or more valves) it is preferred that at least one, and preferably each, valve is a multiple valve, i. e. comprises in one evacuated envelope a plurality of substantially independent electrode assemblies adapted to operate separately or to perform separate functions. Small valves of this character are known in the radio art, and by way of example reference may be made to two types of valve which may be employed, namely, valves known by code numbers 25B8-GT and 70L7-GT. The former comprises in one envelope triode and pentode electrode assemblies, while the latter comprises half-wave rectifier and beam power output electrode assemblies; and they have overall lengths, excluding the base pins, of 2 $\frac{1}{8}$ inches and 2 $\frac{3}{4}$ inches respectively, and each a maximum diametrical width of 1 $\frac{1}{8}$ inches. Alternative valves that may equally well be employed are

those known under the code number 12B8-GT (embodying a triode and a pentode) and 32L7-GT (embodying a diode or $\frac{1}{2}$ wave rectifier and a beam power output).

In order to be operated by current directly from the domestic supply voltage the valve cathode heaters may be connected in series with one another and with a suitable load. In one form of the invention it is preferred that this load shall comprise one or more electric lamps of suitable total voltage and wattage rating and a socket or sockets may conveniently be provided in, or attached to, the receiver casing to receive it or them. If desired an alternative resistance load may be provided, e. g. a resistance component adapted to be plugged or screwed at will, in place of the lamp, into the lamp socket, or as a resistance built into an end cap of the receiver casing suitable to replace the removable end cap which incorporates or supports the lamp socket or sockets. Alternatively such a resistance may be built permanently into the receiver casing and switch means provided to bring it into circuit and to cut out the lamp (without physical replacement) if and when it is desired to operate the receiver without the light. The same or other switch means may be provided or adapted to allow light to be switched on without putting the receiver into operation. Such means may be located at the domestic switch or in the receiver casing. In a further alternative the lamp shade may be formed from a resistance mat the resistance of which forms the load. In a still further alternative I may employ a lamp bulb with a secondary ballast resistance in the same envelope.

It should be understood that the above-described arrangement of series connected cathode heaters does not exclude the use, within the scope of this invention, of any other convenient arrangements, e. g. a series-parallel connection between heaters and/or the load, with or without suitable shunt elements, if necessary, to ensure the required values of voltage and current for the heaters, and the best use of the remaining power not required by the heaters.

In some cases, also, I may employ filament type valves in place of the valves above referred to, in which case direct current may be supplied to the cathodes by means of a suitable rectifier (if the supply is from A. C. mains), and here again a series or parallel or series-parallel arrangement may be adopted.

As an aerial it is preferred to employ one of the electric supply cables and incoming signals may be picked off therefrom by suitable coupling: but if this is not convenient or desirable I may employ a separate aerial of any convenient form, e. g. the wire frame of an electric lamp shade mounted on the same pendant as the receiver. Means may be included in the circuit to eliminate mains hum and/or other interference which may originate from the use of a supply cable as an aerial and/or from the close proximity of any alternative aerial and of the circuit as a whole to the supply leads.

While it is preferred to mount the loudspeaker in the receiver casing, it is within the scope of the invention to employ a receiver, as briefly described above, adapted to feed a separate loudspeaker which may, for example, be in the form of an electric lamp shade or reflector mountable on the pendant in which the receiver is plugged, and the tensioned material forming the shade covering may be used as the loudspeaker diaphragm. As a modification of this arrangement the receiver

casing may itself form the upper portion of the shade, being, for example, a shallow flat or domed box incorporating centrally the loudspeaker, having radial or sectored compartments or recesses to receive lamps and other compartments to house the receiver circuit components, with means round the edge to support beading or other artistic drapery or decoration.

While the shape of the receiver casing may assume any of a number of forms, it is desirable that its lateral dimensions shall be limited in the vicinity of the connector, in order that when it is plugged into an electric socket the casing will not interfere with fittings already mounted on, or adjacent to the socket. This consideration is of less importance where, as suggested above, the casing itself forms part of a fitting, e. g. a lampshade. The centre of gravity of the assembly should be on the axis of the connector in all cases in which the latter is rigidly associated with the receiver casing. It is also preferred that the axis of the loudspeaker shall be in alignment with the said connector axis. The casing may conveniently be formed of moulded parts of any suitable artificial plastic, and the circuit elements mounted upon a separate frame or platform removably insertable into the outer casing for ease of assembly and access.

In one convenient modification the casing may be in the form of a cylinder of circular, rectangular or any other desired horizontal cross-section, or the casing may be slightly conical in or near to one end of which is mounted the loudspeaker, and having in the closure or end cap at the other end a socket suitable to receive an electric lamp which forms the load in the valve cathode heater circuit. By means of a framework or spider extending to the rigid speaker surround or to the casing wall adjacent thereto, there is carried a plug in line with the speaker axis, adapted to engage the socket of a domestic light pendant and thus both support the receiver and supply electric power to the circuit. Alternatively the lamp-socket and the supporting plug may be in interchanged positions, i. e. adjacent to the speaker and at the opposite end of the receiver respectively. In either case suitable adaptors may be provided in order that the user can at will invert the receiver from its normal position and utilise it in the inverted attitude.

In such a casing the frame or platform carrying the valves and other circuit components may be of any suitable form, as for example, it may be in the form of a plate extending across the casing and having the valves on one side, preferably with their axes parallel to the casing axis, and the other components on the other side. Where valves other than the multi-purpose valves above referred to, are employed, the valves may be held between two apertured plates or rings extending across the casing, the remaining components being arranged in the space within the valves and/or on the other face of the plate or plates. In any modification of the invention I preferably dispense with the conventional valve holders or bases, and use spring plugs direct on the leads from the valve components.

To the end of the casing in which is located the loudspeaker there may, if desired, be removably secured a flared mouthpiece forming an extension of the casing wall to provide a horn for the speaker. This mouthpiece may serve as the means for securing the speaker in its seating and may carry the spider or framework bearing the supporting connector. If desired the casing

proper may be slightly curved or tapered to form artistic lines with the flared horn extension.

In alternative designs, the supporting connector may be located on one side of the cylindrical casing along its longest dimension, and the speaker located on the opposite side of the casing, either sunk into, or supported externally of the wall. In the latter arrangement there should be (and in the former arrangement there may be, if desired) a flared horn attached to the casing wall and surrounding the speaker, adapted to protect the speaker, to focus its acoustic output, to carry the lamp-supporting spider and to act as a shade for the lamp. In both these forms the platform carrying the circuit components is preferably inserted in the casing in such a manner that the valve axes are at right angles to the axis of support of the receiver as a whole.

In yet another form, facilitating the use of a loudspeaker with a diaphragm of larger diameter, the supporting connector is attached to the rear of the housing of the speaker movement, while arms inwardly extending from the rigid outer surround of the diaphragm are attached to or engage the casing carrying the circuit components, which casing is thus supported beneath and axially in line with the speaker, and has on its lowermost face a socket to receive the load-lamp.

Yet another manner of mounting the receiver upon a light-pendant involves the use of an adaptor suitable for plugging into the pendant and having a socket to receive the load-lamp. The adaptor has a downwardly extending framework or spider attached or attachable at its lower end to the receiver casing which is thus slung beneath the lamp. The electrical connections within the adaptor are such that current passing through the lamp traverses one limb of the framework or spider to the receiver, and returns from the receiver through another limb to the adaptor and thus to the pendant.

In casings such as described above I may employ a moving coil loudspeaker although I prefer to employ a permanent magnet moving iron loudspeaker with a concave cone-type diaphragm having a diameter of 2½-3 inches. With such a speaker the overall dimensions of the casing can be of the order of 3½ inches by 3 inches by 3 inches, excluding the flared horn, if any, thereon. Alternatively the magnet of the speaker may be energised by D. C. taken from the rectified output of the rectifier, in which case the magnet windings are designed to assist in smoothing the output. In yet another arrangement use may be made of a piezo-electric speaker, which has the advantage of not requiring magnetisation or an output transformer. In all forms the casing may be apertured or louvered to allow cooling ventilation to reach the circuit components and, if necessary, to facilitate outlet of sound from the speaker.

While any desired or convenient form of circuit may be employed in a casing such as indicated above, it is contemplated that a simple three stage circuit will meet many of the needs for which the invention is intended and such a circuit is shown in Figure 1 of the accompanying drawings.

Referring to Figure 1, V1, V2, V3, V4 show valves of the types mentioned above, and the cathode heaters V^a1, V^a2, V^a3 and V^a4 are connected together in series and fed from the domestic supply *a* through a series load, e. g. a lamp *b*, of suitable resistance to reduce the voltage to

the total required across the series heaters. An inductance *c* (forming with the condenser *d* a tunable circuit) is connected between the control grid and cathode of the first stage V1 of the receiver, which may conveniently be a pentode. The output from this first valve is fed through transformer coupling *e* to the control grid of the second stage e. g. a triode detector V2, from which the output is passed by resistance-capacity coupling to the control grid of the third and last stage V3, e. g. a beam power output tetrode, from which the output is fed to the loudspeaker coil *f* through an output transformer *g*. In place of this transformer I may employ a high impedance voice coil in the plate circuit of the output valve. The supply leads are also connected across the cathode heaters and to the anode of the rectifying valve V4, or to the terminals of a small metal or other rectifier, from which the H. T. output is passed through a suitable smoothing circuit, e. g. comprising a choke and earthed condenser, to the anode loads of the other valves.

It will be appreciated that a circuit such as described above is not designed to have a wide range of reception and if desired, therefore, the inductances may be tapped at selected points to provide preset tuning and the receiver thus made adjustable to receive from any one of a limited number of stations by switch, press-button or like means, which may, for example, be the ordinary electric light switch as hereinafter referred to. Alternatively suitable tuning means may be provided, and may be such that the value of either or both inductances can be varied, e. g. by adjusting the number of turns thereon in use, or the coupling between the inductances may be variable, to provide continuous tuning within the frequency range for which the receiver is designed. The means for such adjustment may be of any convenient form, e. g. a rotatable knob extending through the casing wall; or, in accordance with the invention one inductance may be wound upon a cylindrical former axially movable within the receiver casing. The windings of this movable inductance may run against contacts so located that movement of the coil varies the number of turns in circuit; or the other inductance may be wound or housed immovably within the casing so that movement of the first-mentioned coil would increase or decrease the coupling with the second-mentioned coil. If desired adjustment of the associated capacity may be effected simultaneously with, and by the same movement as effects adjustment of the inductance coupling. Such movement may conveniently be effected by means of a lug projecting from the movable elements through a slot in the casing; and a calibrated scale may, if desired, be provided thereagainst.

If desired additional lamp sockets may be provided on the receiver casing so that the user can, if he wishes, enjoy more light than would be provided by the load-lamp. Such additional lamps would be in parallel with the receiver circuit, and may be arranged to be switched on or off by the same switch as substitutes a built-in resistance for the load-lamp (when it is desired to operate the receiver without light from the load-lamp) or may be provided with separate, independently operable, switch means. Such switch means may in either case take the form of a multi-contact selector switch allowing the user to actuate separately or in any combination the receiver and the various lamps.

For the purpose of tuning and/or switching lamps or other circuit components in a receiver

75

of the kind described above or in any other small receiver, there is envisaged, according to this invention, the use of a small relay-operated switch. This may comprise a coil, located across the supply mains or in the H. T. supply, actuated by a switch to operate an armature whereby a pawl is caused to turn a ratchet wheel which carries or moves an on-off switch or the wiper arm of a multi-contact switch. In the latter case, for example, movement of the arm from one contact to the next brings into or removes inductance and/or capacity in the circuit and thus tunes it to a different frequency. The arm may move one step for each depression of the relay-actuating switch. Such an arrangement is more compact than separate press-button tuning to any one of a limited number of frequencies for which the receiver has preset tuning. An example of such tuning for two different frequencies is shown in Figure 1 of the drawings in which a solenoid or relay winding *h* is arranged in the high tension circuit so that the H. T. produced in the rectifier *V4* has to pass through the solenoid windings with the result that as soon as H. T. passes through the circuit, the solenoid is energised. The relay is adapted to operate a spring-load pawl and ratchet mechanism which actuates the switch contacts *h*' so that for successive positions of the ratchet mechanism produced by successive operations of the light switch, the tuned frequency will first be determined by the tuned inductances *c* and *e*, and will then be altered by the switching of the additional pre-set capacitances (or trimmer condensers) *d'* and *e'* across such tuned inductances. Where an energised loud-speaker is used the solenoid may be employed as the switching coil.

If desired, in any of the modifications of the invention described above two or more loud-speakers may be included in the circuit for greater volume of acoustic output. Thus the casing may carry two loud-speakers one on each of opposite ends or sides: or a receiver with one speaker mounted in the casing, as described above, may be used in conjunction with another loud-speaker, e. g. in the form of a lampshade, as also described above.

In Figure 2 I have shown a form of receiver in accordance with the invention applied to a light pendant, the receiver being shown at *i*, the lamp bulb at *k* and the shade at *l*. In this form the speaker is at the bottom of the casing adjacent the lamp, but it could equally well be disposed at the upper side of the casing.

Figure 3 shows a similar arrangement but applied to a lamp standard.

Figure 4 shows the arrangement of radio receiver parts within the casing *i* of Figs. 2 and 3, the reference numerals referring to the same parts as in the diagram of Fig. 1.

It should be understood that the invention is not limited solely to the details of construction and arrangement described above since modifications thereto may be introduced as and when they appear desirable in order to carry the invention into effect and achieve the results indicated under

different conditions and requirements which have to be fulfilled without departing in any way from the scope of the invention. For example, by choosing valve heaters such that when in series the total voltage taken by the heaters is equal to the mains voltage the lamp or other load will not be necessary and in such case if I combine a lamp with the receiver it may be switched on and off for lighting purposes only. Further, when a moving iron speaker movement is employed as above described the winding may be used in the plate circuit of the output valve in place of the transformer, or, alternatively, the relay coil above referred to can constitute the output valve plate impedance, again dispensing with the output transformer.

I claim:

In a combined electric lamp and radio receiving apparatus, a ventilated casing having a longitudinal central axis of symmetry and bounded by two spaced-apart end surfaces both perpendicular to said axis, a complete assembly of radio receiver circuit components removably mounted in said casing for ready removal and repair, a screw-type electrical power connector secured to a central portion of one of said end surfaces, power connections between said connector and said assembly for supplying operating power to the latter, whereby said connector may be screw-coupled to a complementary power supply fixture to energize the radio receiver circuit components and simultaneously to support said casing in a predetermined relationship to said fixture, a screw-type power connector secured to a central portion of the other end surface, power connections from said first connector to said second connector adapted to energize an electric lamp connected to the latter connector, and a loudspeaker mounted entirely within said casing adjacent the first mentioned end surface in a centered position on said axis for directing sound outwardly of said casing.
